HOSTESS CART

Houghton W. Clarke, Evanston, Ill., assignor to Mealpack Corporation, Evanston, Ill., a corporation of Illinois

Application October 25, 1952, Serial No. 21,989

Term of patent 14 years

(Cl. D14—3)

To all whom it may concern:

Be it known that I, Houghton W. Clarke, a citizen of the United States, residing at Evanston, county of Cook, and State of Illinois, have invented a new, original, and ornamental Design for a Hostess Cart, of which the following is a specification, reference being had to the accompanying drawing, forming a part thereof, in which:

Fig. 1 is a perspective view of a hostess cart showing my new design, Fig. 2 is a side view in elevation, Fig. 3 is a top plan view, Fig. 4 is a front view in elevation, and Fig. 5 is a rear view in elevation thereof.

I claim:

The ornamental design for a hostess cart, as shown.
